UNITED STATES PATENT OFFICE.

WILLIAM I. WEEGAR, OF NEW YORK, N. Y.

BATTLE-SHIP.

SPECIFICATION forming part of Letters Patent No. 625,130, dated May 16, 1899.

Application filed May 19, 1898. Serial No. 681,122. (No model.)

To all whom it may concern:

Be it known that I, WILLIAM I. WEEGAR, a citizen of the United States, and a resident of New York, in the county and State of New York, have invented a new and useful Improvement in Battle-Ships, of which the following is a specification.

My invention relates to an improvement in battle-ships with a view to providing a comparatively extensive battery-space while keeping the magazines and propelling mechanism completely shielded by water.

A practical embodiment of my invention is represented in the accompanying drawings, in which—

Figure 1 represents the ship in side elevation. Fig. 2 is a top plan view. Fig. 3 is an end view looking at the bow, and Fig. 4 is a transverse section in the plane of the line 4 4 of Fig. 1.

The hull A of the ship may be of any desired shape in cross-section to suit the particular purposes for which the ship is built, the plan here shown being of the shallow type 25 for use in harbors where there is not great depth of water.

The hull is provided with a deck a, convex in cross-section, which is intended to be sufficiently armored to prevent a shell or shot 30 from piercing it. The deck is extended upon opposite sides beyond the sides of the hull, forming wings a', the under sides of which are concave and the upper sides convex, so that they will tend to prevent the ship from 35 rolling and at the same time guard the upper portions of the sides of the hull near the surface of the water.

Uprising from the hull of the ship at intervals are towers—in the present instance two 40 main towers B B', preferably located at about equal distances from the opposite ends of the ship, and a pair of end towers C C', both of which are conning-towers. There is also a tower, denoted by D, located amidships for the 45 purpose of protecting the smoke-stacks leading from the boilers. Each of the towers may be provided with one or more staircases of any well-known or approved form leading from the interior of the hull of the ship.

50 The several towers B B', C C', and D are connected by an armored horizontal chamber,

denoted as a whole by E and spaced from the crown-deck a of the hull. The several towers referred to form a support for the armored chamber E and between it and the deck are 55 made of polygonal form in cross-section—in the present instance square with a diagonal of the square in alignment with the longitudinal axis of the hull, so that they present sharp corners to the front and rear. The 60 polygonal portions of the towers intermediate of the armored chamber and the deck are denoted, respectively, by b b', c c', and d. The chamber E extends continuously in the present instance from a point in front of the forward tower C to a point to the rear of the rear tower C' and has an irregular diamond shape 65 in cross-section, as clearly indicated in Fig. 4—that is, its roof slants downwardly in opposite directions from a longitudinally-extending horizontal ridge e—the opposite sides of the bottom of the said chamber extending from the opposite edges of the top of the chamber toward one another in a downwardly-inclined direction and meeting along a line e' 70 in the vertical plane of the ridge e.

The opposite sides of the roof are denoted, respectively, by e² e³, and the opposite sides of the bottom are denoted, respectively, by e⁴ e⁵.

Broadside-guns are mounted at intervals 80 throughout the length of the chamber E and also at its opposite ends, it being intended that the armor of the chamber E and the towers shall be sufficiently heavy to effectually turn to one side any projectile which might 85 strike it. The towers B B' are intended for mounting heavy guns above the chamber E. The shape is such that no matter from what direction in a substantially horizontal plane a projectile may strike that portion of the ship 90 above water it will strike an inclined surface and will be glanced off, save only the very improbable chance that the apex of the projectile impinge directly against the sharp edge of the chamber or tower, and even then it is intended that the armor be sufficient to withstand it. While so protected by water from projectiles which may be directed toward it, the ship is at the same time seaworthy, for the reason that the gun-chamber is spaced 95 above the deck, where it will permit the free 100 swash of the waves across the deck beneath

it without interfering with the gun-ports in the armored chamber and towers.

It is assumed, of course, that the hull of the ship shall be ballasted by her engines, fuel, 5 and, if need be, other ballast to make her stable, and this problem is one that can be easily solved by those accustomed to ship-building.

In addition to her guns the above-described 10 battle-ship is adapted for shooting torpedoes from points both below and above the surface of the water—as, for example, through the ports F along the side and through the port f at the bow, which may be in action slightly 15 above or slightly below the surface of the water, as desired.

It is obvious that the arrangement of the 20 guns, the number and location of the towers, and the shape of the armored longitudinal gun-chamber in cross-section may be changed without departing from the spirit and scope of my invention. Hence I do not wish to limit

myself strictly to the structure herein set forth; but

What I claim is—

25 A battle-ship comprising a hull, conning-towers uprising from the hull at or near its opposite ends, gun-towers uprising from the hull intermediate of the conning-towers, a smoke-stack tower uprising from the hull and 30 a horizontal gun-chamber connecting the several towers and spaced from the deck of the hull, the said conning and gun towers extending above the roof of the horizontal gun-chamber, substantially as set forth.

35 In testimony that I claim the foregoing as my invention I have signed my name, in presence of two witnesses, this 14th day of May, 1898.

WILLIAM I. WEEGAR.
